UNITED STATES PATENT OFFICE.

ARMANDO C. CABALLERO, OF NEW YORK, N. Y., ASSIGNOR TO THE UNIVERSAL CODING SYSTEM CO. LTD., OF VALPARAISO, CHILE, A CORPORATION OF CHILE.

CRYPTOGRAPHIC APPARATUS.

Application filed September 21, 1920. Serial No. 411,700.

To all whom it may concern:

Be it known that I, ARMANDO C. CABALLERO, a citizen of the Republic of Chile, and a resident of New York city, in the county 5 and State of New York, have invented certain new and useful Improvements in Cryptographic Apparatus, of which the following is a specification.

My invention relates to a cryptographic 10 apparatus, and has for its principal object the production of such an apparatus, which is simple and easy to use, certain and accurate in its results and which ensures secrecy, rapidity and increased economy in 15 the transmission of messages, being adapted to any telegraphic code in any language, and serving to transform old code words into more concise and otherwise better code words and to enrich the vocabulary in any 20 code.

My invention more specifically relates to 25 the method of cryptography whereby a code number (which may correspond in one of the codes to a given message) of a certain number of digits, five for example, may be transformed or translated into an artificial word of fewer letters or other signs, for example, four in the case of a number with 30 five digits, two of which may be consonants and two vowels, the consonants and vowels always forming syllables; and the invention comprises apparatus which may assume many different forms, to facilitate such 35 translation.

With my invention, two numbers of five 40 digits each, for example, may be transformed or translated into an artificial word of eight letters, for example, containing four consonants and four vowels, an extra checking syllable being added, forming altogether a word of ten syllables. The said extra syllable is a check or a control by which it may 45 be determined whether the numbers represented by the eight preceding letters have been correctly translated or whether there has been any alteration in the transmission.

Other features and advantages of my invention will appear more fully in the fol-

lowing detailed description and appended claims.

In order that the invention may be clearly understood, attention is hereby directed to the accompanying drawings forming a part of this invention and in which Figure 1 is a view in elevation of one form of apparatus 55 embodying my invention:

Fig. 1^A is a like view of the same but arranged for a different key; and

Fig. 2 is a section thereof taken on line 2—2 of Fig. 1.

Fig. 3 is a view in elevation of a modification.

Fig. 4 is a section of the latter on line 4—4 of Fig. 3.

Referring to the drawings, there are four 65 sectors or quadrants marked at their inner portions with letters Sg, Md, Sp, and At, the sectors being separated by the lines 1, 2, 3 and 4. Each sector contains five parts or subdivisions marked A, B, C, D and E. 70 The part or subdivision A is subdivided into a number of equal portions each of which contains a digit or a number composed of two digits. These subdivisions represent the "hundreds" of the code number to be 75 translated. The part or subdivision B is similarly subdivided, each sub-division containing a consonant. The part or subdivision C is likewise subdivided, each sub-division containing a number formed of 80 two digits. The numbers in subdivision C represent the "thousands" in the code number. The parts D and E contain subdivisions corresponding to the subdivisions in 85 the columns A, B and C, the subdivisions of part D containing vowels and the sub-divisions of part E containing numbers formed of two digits. The part or subdivision E represents the "tens" and "units" of the code number. As shown, the various parts A, B, 90 C, D and E are subdivided by radial lines, the said parts being in the form of concentric rings.

The indications Sg, Md, Sp and At, Spanish abbreviations for "Following" (Seguido), 95 "Middle" (Medio), "Separated" (Sepa-

das), "Arranged before" (anteponerse), express respectively that each vowel should follow a consonant, that the two vowels should be placed between the two consonants, that the two vowels should be placed separately at the two sides of the consonants and that one vowel should precede each consonant.

If we designate by XX the two consonants of a word and by AA the two vowels, then Sg will indicate the arrangement XAXA; Md will indicate the arrangement XAAX; Sp will indicate the arrangement AXXA; and At will indicate the arrangement AXAX.

In use, the first consonants of the word will be found below or inwardly of the "thousands" of the number as shown by the part or subdivision C. The second consonant will be found immediately above or outwardly of the "hundreds" of the number as shown in subdivision A, and if the number contains neither "thousands" nor "hundreds" it will be treated as if the "thousands" and "hundreds" places were furnished with zeros.

The first vowel will be found immediately below or inwardly of the "tens" and "units" of the number as shown in the part or subdivision E. The second vowel will be found in the part or subdivision D directly above or outwardly of the figure representing the "hundreds" of the number in part or subdivision A.

When the exact "thousands" is not shown or contained in part or subdivision C the first consonant is determined by taking the next smaller number of "thousands" in the subdivision C to determine the first consonant, the "thousands" remaining being associated with the "hundreds" by being placed before the same in the determination of the second consonant.

Where the exact "tens" and "units" are not found in the part or subdivision E the next smaller number in this part or subdivision is taken to determine the first vowel; and the difference between the "tens" and "units" of the number being translated and of the number selected in the part or subdivision E will indicate the number in the part or subdivision A for locating directly outwardly of the same the second vowel.

The collocation of the vowels and consonants will be determined from the notations Sg, Md, Sp and At which occur in the sector in which the "tens" and "units" of the number being translated are found. In instances where the "tens" and "units" found in subdivision E are not the precise "tens" and "units" of the number but the nearest lower "tens" and "units," the collocation is still determined by the sector containing the "tens" and "units" found, that is, the sector of the first vowel.

Applying the invention to a transmission of a secret message let us take for example, the message—"Throwing out covered cargo went aground over her anchors." This message is represented in code by figures and ordinary code words, as follows:

Figures or numbers.	Ordinary code words.	Message.
08208 19874	Calliule..... Garranche.....	Throwing out covered cargo. Went aground over her anchors.

With my invention, the message as expressed in numbers is translated into one word—FACIOLWOTA—in the following manner, the word or letters FACI corresponding with the number 08208, the word or letters OLWO corresponding to the number 19874, and the letters TA giving the control or check. By the addition of words formed in the same way as "FACT" and "OLWO" to a code, a material increase in the vocabulary of the code may be made.

Referring to part or subdivision C, the "thousands" "08" indicate the first consonant —F. The "2," the hundreds in part or subdivision A indicate—C, as the second consonant. The "08" representing "tens" and "units" is not found in part or subdivision E so that the next lesser number in said subdivision is taken; to wit "05" to indicate the first vowel. This vowel in this case is—A.

To determine the second vowel the "05" used to locate the first vowel is subtracted from "08" which represents the actual number of the actual "tens" and "units" in the number translated, which gives "3" as the numeral in part or subdivision A for locating the second vowel. This numeral indicates the vowel I. As the "tens" and "units" "08" are found in the sector or quadrant which is marked Sg the vowels should follow the consonants and accordingly the word corresponding to the number 08208 is found to be the word "FACT." By reference to the foregoing description, it can be easily ascertained that the word corresponding to the number 19874 is OLWO. Referring to part or subdivision C, the next smaller number of "thousands" (18) indicates the first consonant—L. The remaining thousand

when associated with the hundreds gives 18 hundred which, referring to subdivision A, gives —W— as the second consonant. Referring to the subdivision E, the next smaller number of "tens" and "units" (70) gives —O—for the first vowel and "Sp" (separated) for the collocation. The remaining units (4), referring to subdivision A, give —O— for the second vowel. The word corresponding to 19874 is accordingly OLWO.

To determine the checking letters the second number is written immediately after

the first number and the resulting number is decomposed into numbers each comprising two digits by spacing off two digits at a time beginning at the left hand end of the resulting number.

These numbers comprising each two digits are added together and from the "tens" and "units" of the sum a consonant and vowel are determined, the exact or next lower "tens" and "units" in subdivision E determining the consonant and the remaining "units" in subdivision A determining the vowel. In the case in question we have $08+20+81+98+74=281$. 80, the next lower "tens" and "units" in part or subdivision E indicates the consonant T and the remaining 1 in part or subdivision A indicates the vowel A. The checking syllable is accordingly TA so that the complete word into which the numbers 20 are translated is FACIOLWOTA.

Translation of a message.

Let us suppose that the word to be translated is faciolwota.

25 The final or check letters are separated and the remaining eight letters are divided into halves, leaving

FACI—OLWO—TA

30 Reversing the process explained above, F, 1st consonant, equals 08 thousands. C, 2nd consonant, equals 2 hundreds.

The first vowel is found in the quadrant Sg, as shown by the arrangement of consonants and vowels, so that A, 1st vowel, equals 05 tens and units and

I, 2nd vowel, equals 3 units (subdivision A)

40 The first number is accordingly 08208, obtained by associating the thousands, hundreds, tens and units into one number, the units being added to the tens and units.

45 Similarly the second number is found to be 19874 as follows:

L, first consonant, equals 18 thousands.

W, second consonant, equals 18 hundreds.

The first vowel is found in quadrant "Sp." as shown by the arrangement of consonants and vowels, so that

O, first vowel, equals 70 tens and units.

O, second vowel, equals 4 units.

50 As the maximum difference between consecutive tens and units in subdivision E is —5—, the units for the second vowel must be less than 5 and must be in the quadrant —Sg—.

Check or control.

60 The message is verified by the receiver by determining from the numbers found by him, the appropriate control or check syllable, as described above. If the checking letters are found by the receiver to be the same as the final letters of the message it is

proven that the message is received as sent.

Referring to the form of the invention represented in the drawing, this form comprises four movable concentric rings B, C, D, E and one central disk A concentric therewith. These rings B, C, D, E and the disk A contain the data already described in connection with the parts or subdivisions bearing the same reference letters.

One of the principal objects of this apparatus is to facilitate the changing of the key, which is done by rearranging the relative positions of the different parts A, B, C, D, and E among themselves, according to the combination which it is desired to agree upon between two correspondents. In this manner, it is possible to translate the same number into distinct words, as varied as the keys which it is desired to agree upon, the apparatus affording a considerable number of changes.

75 The apparatus of Fig. 1 corresponds, to the system whose key is: 05—A—02—B—1, these being in radial alinement.

80 The key may be varied, as desired, to maintain the greatest possible secrecy. As shown, the disk A has arms 5, 6, 7, 8 arranged at right angles to each other and containing the quadrant defining lines 1, 2, 3, and 4. The disk is mounted upon a threaded stud 9 and may be secured in position or loosened to facilitate changing the key by manipulation of the nut 10 on the said stud. The rings B, C, D, E, may be provided with depressions or low projections 11, 12, 13 and 14, respectively to facilitate shifting of any one or more of the rings. The arms 5, 6, 7 and 8 bear upon the said rings and tend to hold the same in position when the disk A is secured in position.

90 I shall now explain with a practical example transmitting with the apparatus described above twelve digits in a perfectly legible word of ten letters, which amply fulfills cable conditions, and moreover has a check or verification.

95 Take, for example, the "Western Union" code—base or key:—45—U—36—H—1. (See Fig. 1A.)

105

100

110

115

120

125

Commercial House Western Union.		Signification.	With my system.
Code number.	Code word.		
157077	Vuloatus	Ontarie (Ontario) $1\frac{1}{2} \times 5\frac{1}{2}$	2 HAASVORIOW.
133969	Fapujaria		

To send the code number of the telegram when the digits, as in this case, are six to each word, one works as follows:

From each number is subtracted a sufficiently large amount to bring the number within the range of the apparatus. In this

case, this is one hundred twenty thousand (120,000) because this instrument has been constructed for forty thousand combinations, as will be seen by reference to subdivision C.

This gives the following results:

First telegram.	Second telegram.	Proof or check.
157077 -120000	138969 -120000	(15) 7 0 7
37077—corresponding to my word HAAS.	18969—corresponding to my word VORI.	7 (13) 8 9 6 9 0 5-WO

Word which results—(HAASVORIOW).

13. In deriving the word HAAS: 36 thousands, referring to subdivision C, give (in Fig. 1^A) —H— as the first consonant; 10 hundreds, referring to subdivision A, give —S— as the second consonant; 75 “tens” and 20 “units,” referring to subdivision E, gives —A— for the first vowel and “Md” (middle) for the collocation; the remaining 2, units, referring to subdivision A, give —A— as the second vowel.
25. In deriving the word “VORI”: 18 thousands give —V— as the first consonant; 9 hundreds give —R— as the second consonant; 65 tens and units give —O— as the first vowel and “Sg” (following) as the 30 collocation; 4 remaining units give —I— as the second vowel.

As to the check, the addition above give 05— tens and units. Referring to subdivision —E—, these tens and units give 35 —W— as the consonant. There being no remaining units, subdivision A indicates —O— for the vowel.

I indicate the control or check of the same telegram with the vowel placed before the 40 consonant, whereas for a number below 40,000 it is placed after the consonant. In the check, the entire tens and hundred thousands of each number are considered as one digit and are added in the column in 45 which the number would have been placed had it contained one digit. Thus in the above example the number 157077138969 is divided (15) 7 07 7(13) 89 69 as indicated above, the sum being 405. The 4 is dropped 50 and the number 05 in tens and units gives O W for the check. In the receipt of the message, the arrangement of letters in the final syllable shows a subtraction was originally made, the vowel being placed before 55 the consonant. The number to be subtracted is agreed upon in advance when the code used has more code numbers than the apparatus, in this particular case in question 40,000.

60. In Figs. 3 and 4, I have shown a modification of my invention employing 5 concentric rings A', B', C', D', E', each movable relatively to the other upon the base α . The expression At, Sg, Md, Sp, designating the collocation of consonants and vowels, are

placed on the base α . This structure allows adjustment of all the rings relatively to the base, and an increased number of changes of key may be therefore obtained. The rings may be held in place by the arms 5', 6', 7', and 8' similarly as the arms 5, 6, 7 and 8 of Figs. 1 and 2 hold the corresponding rings in place.

Having thus described my invention, what I claim and desire to secure by Letters 75 Patent of the United States is:

1. In apparatus of the class described, a device having subdivisions corresponding respectively to certain collocations of signs and having other subdivisions containing signs and figures for translating a number into signs and vice versa.

2. In apparatus of the class described, a device having sector shaped subdivisions corresponding respectively to certain collocations of letters and having within said subdivisions other subdivisions containing letters and figures for translating a number into the letters of a word, and vice versa.

3. In apparatus of the class described, a device having sector shaped subdivisions corresponding respectively to certain collocations of letters and having within said subdivisions arcuate subdivisions, one of which contains vowels, another consonants, and others digits or combinations of digits, whereby a number may be translated into a legible word, and vice versa.

4. In apparatus of the class described, a device having subdivisions corresponding respectively to certain collocations of consonants and vowels, and having within said subdivisions parts or subdivisions, one of which contains vowels, another consonants, and others numerals representative respectively of thousands, hundreds, and tens and units of a number.

5. In apparatus of the class described, a device having sector shaped subdivisions corresponding respectively to certain collocations of consonants and vowels, and having within said subdivisions arcuate parts or subdivisions, one of which contains vowels, another consonants, and others numerals representative respectively of thousands, hundreds, and tens and units of a number.

6. A device having parts, one of which contains vowels, another consonants, and others sets of digits or combinations of digits whereby a number may be translated into a legible word, and vice versa, there being separate parts corresponding to certain decimal positions in the number to be separately transformed.

7. A device having parts, one of which contains vowels, another consonants, and others digits or combinations of digits whereby a number may be translated into a legible word, and vice versa, there being

separate parts corresponding to certain decimal positions in the number to be separately transformed, one of said parts being movable relatively to the rest to change the key 5 of the apparatus.

8. A device having parts, one of which contains vowels, another consonants, and others digits or combinations of digits whereby a number may be translated into 10 a legible word, and vice versa, there being separate parts corresponding to certain decimal positions in the number to be separately transformed, each of said parts being movable relatively to every other sub- 15 division to change the key of the apparatus.

9. In apparatus of the class described, a device having subdivisions corresponding respectively to certain collocations of consonants and vowels, and having within said 20 subdivisions parts or subdivisions, one of which contains vowels, another consonants, and others numerals representative respectively of thousands, hundreds, and tens and units of a number, each of said parts being 25 movable relatively to every other of said parts to change the key of the apparatus.

10. The combination of a base, having a plurality of concentric members movably

mounted thereon, one of said members containing vowels, another consonants, and a plurality of other members containing numerals representative respectively of thousands, hundreds, and tens and units. 30

11. The combination of a base, having a plurality of concentric members movably 35 mounted thereon, one of said members containing vowels, another consonants, and others numerals representative respectively of thousands, hundreds, and tens and units, one of said members containing subdivisions 40 corresponding respectively to certain collocations of vowels and consonants.

12. The combination of a base, having a plurality of concentric members movably 45 mounted thereon, one of said members containing vowels, another consonants, and others numerals representative respectively of thousands, hundreds, and tens and units, one of said members containing subdivisions corresponding respectively to certain collocations 50 of vowels and consonants, and means for securing said members in position on said base.

In testimony whereof, I have signed by name to this specification.

ARMANDO C. CABALLERO.
